[57] ABSTRACT

A static flip-flop circuit wherein an input terminal and an output terminal of a first inverter circuit are respectively feedback-connected to an output terminal and an input terminal of a second inverter circuit, complementary input signals are respectively applied to an input terminal of either one of the field-effect transistors connected in series between the input terminal of the first inverter circuit and ground and to an input terminal of either one of the field-effect transistors connected in series between said input terminal of the second inverter circuit and ground, the first pulse signal is applied to a field-effect transistor connected between an output terminal of said flip-flop circuit and the output terminal of either one of the first and second inverter circuits, and the second pulse signal differing in phase from said first pulse signal is applied to an input electrode of the other of the field-effect transistors connected to the input terminal of the first inverter circuit and to an input electrode of the other of the field-effect transistors connected to the input terminal of the second inverter circuit.

FLIP-FLOP CIRCUIT

BACKGROUND OF THE INVENTION

1. Field of the Invention

The present invention relates to a flip-flop circuit, and more particularly to a static flip-flop circuit employing insulated gate field-effect transistors.

2. Description of the Prior Art

Flip-flop circuits constituted of insulated gate field-effect transistors (IGFET's) are broadly classified into two types; the dynamic flip-flop circuit and the static flip-flop circuit. Although the former is simpler in construction, the latter is more preferable in some cases in view of its retentivity for information.

FIG. 1 shows an example of the dynamic flip-flop circuit which is generally used. Referring to the figure, T₁ - T₆ designate insulated gate field-effect transistors (hereinafter shortly termed the transistors). The transistor T₁ is connected through the transistor T₂ between a power source terminal (-V_{DD}) and ground, and has its gate electrode connected to an input terminal IN - T₆ designate insulated gate field-effect transistors (hereinafter shortly termed the transistors). The transistor T₁ is connected through the transistor T₂ between a power source terminal (-V_{DD}) and ground, and has its gate electrode connected to an input terminal IN through the transistor T₃ receiving a clock signal ϕ_1 as an input. The transistor T₄ is connected through the transistor T₅ between the power source terminal (-V_{DD}) and ground. The transistor T₆ is connected between the gate electrode of the transistor T₄ and the juncture of the transistors T₁ and T₂, and receives a clock signal ϕ_2 as an input. An output terminal OUT is connected to the juncture between the transistors T₄ and T₅.

With such a construction, the pulse frequency of each of the clock signals ϕ_1 and ϕ_2 to be applied to the field-effect transistors T₃ and T₆, serving as transfer gates, is determined by the time constant between the gate capacity and the leakage resistance of the particular transistor, and requires a frequency exceeding a certain prescribed value. Accordingly, as the clock pulses ϕ_1 and ϕ_2 , pulses regularly repeated are generally employed, and control signals with steady state portions cannot be adopted.

FIG. 2 shows an example of the static flip-flop circuit composed of field-effect transistors. The flip-flop circuit in the figure comprises a first inverter circuit constructed of transistors T₁₁ and T₁₂, a second inverter circuit constructed of transistors T₁₃ and T₁₄, a third inverter circuit constructed of transistors T₁₅ and T₁₆, and transistors T₁₇, T₁₈ and T₁₉ for transfer gates. The second inverter circuit and the third inverter circuit are connected in cascade. The output terminal of the third inverter circuit is connected for feedback through the transfer gate transistor T₁₈ to the input terminal of the second inverter circuit, and an information is retained by the feedback loop. The contents of the information retained within the above feedback loop depend on the state of the output of the first inverter circuit at the time when the transfer gate transistor T₁₇ is rendered conductive. A clock signal ϕ_2 is applied to the gate electrode of the transistors T₁₈ and T₁₉, while a clock control signal $\phi_{1,r}$ differing in phase from the clock signal ϕ_2 is applied to the gate electrode of the transistor T₁₇.

The respective drain electrodes of the load transistors T₁₂, T₁₄ and T₁₆ are connected to receive a DC supply voltage V_{DD}, and the respective gate electrodes are connected to receive a DC supply voltage V_{GG} which is higher than the DC supply voltage V_{DD} by approximately the threshold voltage of the transistors.

Herein, voltages to be applied to the gate electrodes of the transfer gate transistors T₁₇, T₁₈ and T₁₉ require, on account of the well-known substrate effect, high voltage levels as in the load transistors T₁₂, T₁₄ and T₁₆, for example, the same level as the DC supply voltage V_{GG}. The substrate effect arises in such manner that, in the case where the substrates of the respective transistors are commonly connected to a reference potential source, for example, in an integrated semiconductor circuit, the respective transistors possess a single, common semiconductor substrate, voltages are exerted between the source electrodes of the transistors and the substrates thereof. The clock signal ϕ_2 is therefore generated at a high voltage level by, for example, an astable multivibrator outside the integrated semiconductor circuit device.

On the other hand, the clock control signal $\phi_{1,r}$ is generated in such a way that a logic operation is performed between a clock signal ϕ_1 (not used in the circuit of FIG. 1), similarly generated by an astable multivibrator or the like at a high voltage with a different phase from the clock signal ϕ_2 , and another pulse signal. The logic operation is performed by a logic circuit formed in the same way as the flip-flop circuit in the integrated semiconductor circuit in which the flip-flop circuit is constituted. The output potential of the clock control signal lowers to substantially the same potential as the DC supply voltage V_{DD}. In general, accordingly, level transformation is carried out in a circuit outside the integrated semiconductor circuit device in order to raise the output potential, and a clock control signal of high level is thus produced. It is also considered that the output level of the logic circuit is raised by adding one further power source in the identical integrated semiconductor circuit device. In any case, however, it is unavoidable to increase the number of external terminals of the integrated circuit device.

SUMMARY OF THE INVENTION

The principal object of the present invention is to provide a flip-flop circuit in which the writing or reading control for information can be made with a control signal of low level.

45 BRIEF DESCRIPTION OF THE DRAWINGS

FIG. 1 is a circuit diagram showing an example of a prior art dynamic flip-flop circuit as already described;

50 FIG. 2 is a circuit diagram showing an example of a prior art static flip-flop circuit as already referred to;

FIG. 3 is a circuit diagram showing an embodiment of a flip-flop circuit according to the present invention; and

55 FIGS. 4a - 4c are waveform diagrams of pulses employed in the circuits of FIGS. 1 to 3.

PREFERRED EMBODIMENT OF THE INVENTION

60 The flip-flop circuit according to the present invention will be described in detail hereunder with reference to the accompanying drawings.

65 FIG. 3 illustrates an embodiment of the flip-flop circuit according to the present invention. In the figure, IN₁ indicates an input terminal to which an input signal is supplied; IN₂ is an input terminal to which a control signal $\phi_{1,r}$, as illustrated in FIG. 4(c), is supplied; and IN₃ is an input terminal to which a clock signal ϕ_2 , as

illustrated in FIG. 4(a), differing in phase from the control signal ϕ_{1x} , is supplied.

A transistor T_{20} has its gate electrode connected to the input terminal IN_1 . The transistor T_{20} is connected between a power source terminal ($-V_{DD}$) and ground through a transistor T_{21} which has its gate electrode connected to a power source terminal ($-V_{GG}$). A transistor T_{22} has its gate electrode connected to the input terminal IN_2 , and one of its output electrodes is grounded. A transistor T_{23} has its gate electrode connected to the juncture of the transistors T_{20} and T_{21} , and one of its output electrodes is connected to the other output electrode of the transistor T_{22} . A transistor T_{24} has its gate electrode connected to the power source terminal ($-V_{GG}$). The transistor T_{24} is connected between the other output electrode of the transistor T_{23} and the power source terminal ($-V_{DD}$). Shown at T_{25} and T_{26} are transistors each of which has one of its output electrodes grounded, which transistors are feedback-connected to each other; accordingly, the other output electrodes of the transistors T_{25} and T_{26} are cross-connected to the respective gate electrodes of the other transistor. A transistor T_{27} has its gate electrode connected to the power source terminal ($-V_{GG}$). The transistor T_{27} is connected between the other output electrode of the transistor T_{26} and the power source terminal ($-V_{DD}$). A transistor T_{28} has its gate electrode connected to the input terminal IN_2 , and one of its output terminals is grounded. A transistor T_{29} has its gate electrode connected to the input terminal IN_1 . The transistor T_{29} is connected between the gate electrode of the transistor T_{25} and the other output electrode of the transistor T_{28} . A transistor T_{30} has its gate electrode connected to the input terminal IN_3 . The transistor T_{30} is connected between the juncture of the other output electrodes of the transistors T_{23} and T_{25} and the output terminal OUT .

As the transistors T_{20} – T_{30} , insulated gate field-effect transistors are employed. The transistors T_{21} , T_{24} and T_{27} are loads, respectively. The transistors T_{24} and T_{25} and the transistors T_{26} and T_{27} constitute the first and second inverter circuits, respectively. The transistors T_{22} and T_{29} receive complementary input signals so as to prevent both of these transistors from being rendered conductive at the same time and the state of the flip-flop circuit from accordingly becoming indeterminate. The clock pulses ϕ_2 have a period which is determined by the time constant among the gate capacity C of the next stage to be connected to the output terminal OUT , the leakage resistance of the transistor T_{19} , etc. In this case, the control signal ϕ_{1x} may have a voltage level exceeding approximately the threshold voltage V_{th} ($V_{th} < V_{GG}$). Accordingly, the control signal ϕ_{1x} may be, for example, of the same value as the level of the input signal.

The transistors are made in, for example, an integrated semiconductor circuit, the semiconductor substrate of which is grounded.

With such a construction, when the transistors T_{22} and T_{28} are rendered conductive by the control signal ϕ_{1x} , a new information is written in by the input signal supplied to the input terminal IN_1 . The information is statically retained by the feedback circuit of the transistors T_{24} – T_{27} .

In this case, one output electrode of each of the transistors T_{22} and T_{28} to which the control signal ϕ_{1x} is supplied is grounded, and the source electrode of each

transistor and the substrate are maintained at the same potential. In consequence, the problem of the substrate effect as previously stated is eliminated. The transistors T_{22} and T_{28} can be reliably driven by the control signal ϕ_{1x} of the low voltage.

Although, in the embodiment, the control signal ϕ_{1x} is supplied to the input terminal IN_2 , the invention is not restricted thereto. By way of example, a clock signal ϕ_1 may be supplied which, as illustrated in FIG. 10 4(b), differs in phase from the clock pulses ϕ_2 and effects triggering regularly.

Although, in the embodiment, the output is taken out through the transistor T_{30} from the output terminal of the first inverter circuit, namely, the juncture between the transistors T_{24} and T_{25} , the invention is not restricted thereto. The output may also be taken out through the transistor T_{30} from the output terminal of the second inverter circuit, namely, the juncture between the transistors T_{26} and T_{27} .

Although, in the embodiment, the transistors T_{22} and T_{23} are transistors T_{28} and T_{29} are connected as shown in FIG. 3, the invention is not restricted thereto. It is also possible to connect the transistors T_{22} and T_{23} with the respective positions reversed, and to connect the transistors T_{28} and T_{29} with the respective positions reversed. That is to say, it is also possible to apply the complementary input signals to the transistors T_{22} and T_{28} , and to apply the control signal ϕ_{1x} to the transistors T_{23} and T_{29} . In this case, if the transistors on the ground side are non-conductive, the transistors on the load side need not be rendered conductive. If the transistors on the ground side are conductive, the source electrodes of the transistors on the load side fall to a potential approximately equal to ground potential. In either case, the substrate effect does not become a problem.

As described above, with the flip-flop circuit according to the present invention, the substrate effect is out of question as for the transistors to which the control signal is applied. The circuit is accordingly very advantageous in that the writing and reading control of information can be effected with the control signal of low level.

What is claimed is:

1. A flip-flop circuit comprising a first inverter circuit consisting of a first field-effect transistor in series with a first load, a second inverter circuit consisting of a second field-effect transistor in series with a second load, third and fourth field-effect transistors connected in series between an input terminal of said first inverter circuit and ground, fifth and sixth field-effect transistors connected in series between an input terminal of said second inverter circuit and ground, said input terminals and output terminals of said first and second inverter circuits being feedback-connected therebetween, first means for applying complementary first pulse signals respectively to an input electrode of one of said third and fourth field-effect transistors and an input electrode of one of said fifth and sixth field-effect transistors, a seventh field-effect transistor connected between an output terminal of said flip-flop circuit and an output terminal of one of said first and second inverter circuits and connected to receive a second pulse as an input, and second means for applying a first pulse signal different in phase from said second pulse signal to an input electrode of the other of said third and fourth field-effect transistors and an input electrode of the other of said fifth and sixth field-effect transistors.

2. A flip-flop circuit as defined in claim 1 wherein said first means includes an eighth field-effect transistor connected to the input electrode of said one of said third and fourth field-effect transistors and a source of said first pulse signals connected to the gate electrode of said eighth field-effect transistor.

3. A flip-flop circuit as defined in claim 1 wherein said first means includes an eighth field-effect transistor connected to the input electrode of said one of said fifth and sixth field-effect transistors and a source of

said first pulse signals connected to the gate electrode of said eighth field-effect transistor.

4. A flip-flop circuit as defined in claim 1 wherein said first and second loads are provided as ninth and tenth field-effect transistors, respectively.

5. A flip-flop circuit as defined in claim 1 wherein said seventh field-effect transistor is connected to said first inverter circuit.
